United States Patent [19]

Podhrasky

[11] Patent Number: Des. 297,221

[45] Date of Patent: ** Aug. 16, 1988

[54] WALK-THROUGH METAL DETECTOR

[75] Inventor: Robert J. Podhrasky, Dallas, Tex.

[73] Assignee: Garrett Electronics, Inc., Garland, Tex.

[**] Term: 14 Years

[21] Appl. No.: 792,295

[22] Filed: Oct. 28, 1985

[52] U.S. Cl. D10/106

[58] Field of Search 340/568, 571, 572; D10/104, 106, 116, 121

[57] CLAIM

The ornamental design for a walk-through metal detector, as shown.

DESCRIPTION

FIG. 1 is a front perspective view of a walkthrough metal detector showing my new design;

FIG. 2 is a rear perspective view thereof;

FIG. 3 is a top plan view thereof;

FIG. 4 is a front elevational view thereof;

FIG. 5 is a right side elevational view thereof;

FIG. 6 is a rear elevational view thereof;

FIG. 7 is a left side elevational view thereof; and

FIG. 8 is a bottom plan view thereof.
